UNITED STATES PATENT OFFICE.

JAMES THOMAS AND WILLIAM R. THOMAS, OF CATASAUQUA, PENNSYLVANIA.

INSULATOR FOR USE ON ELECTRIC RAILWAYS.

SPECIFICATION forming part of Letters Patent No. 644,646, dated March 6, 1900.

Application filed December 12, 1899. Serial No. 740,077. (No model.)

To all whom it may concern:

Be it known that we, JAMES THOMAS and WILLIAM R. THOMAS, citizens of the United States, residing at Catasauqua, in the county 5 of Lehigh and State of Pennsylvania, have invented certain new and useful Improvements in Insulators for Use on Electric Railways; and we do hereby declare the following to be a full, clear, and exact description of the invention, such as will enable others skilled in the art to which it appertains to make and use the same.

Our invention relates to improvements in insulators, and particularly to that class of 15 insulators which are adapted for use upon electric railways.

It consists in a device for insulating a conductor comprising a base, an insulating-block having a recess adapted to fit upon a projecting portion of the said base, and a conductor-supporting cup fitting upon and inclosing the other portion of the said block, means for securing the parts together, and means for holding the conductor in position upon the said 25 cup.

It also consists in certain other novel constructions, combinations, and arrangements of parts, as will be hereinafter fully described and claimed.

30 In the accompanying drawings, Figure 1 represents a view of an insulator, portions being shown in elevation and the remainder in central section; and Fig. 2 represents a top plan view of the insulator.

35 1 in the drawings represents an insulator block or piece, 2 a base for supporting the same, and 3 an attaching-cup for holding a conductor, as 4.

The base 2 is preferably made with a broad 40 attaching portion, as 5 5, provided with suitable bolt or nail holes, by which the same may be secured to any suitable support. The central portion of the base 2 projects outwardly to a considerable distance and is preferably 45 formed with many sides, it being shown in the drawings with eight side faces. The projecting portion 6 of the base 2 is adapted to extend into a recess or socket 7, formed in one end of the insulator-block 1. The recess 7 is 50 preferably made with a number of faces cor-

responding to the faces upon the base 2, and when the insulating-block is placed upon the base a suitable cement, as at 8, is interposed between the said base and insulating-block. If desired, the base 2 may be provided with 55 spacing projections, as 9 9, on its outer end, so as to hold the insulating-block at proper distance therefrom.

The insulating-block 1 is made of a suitable insulating material—such as porcelain, 60 glass, rubber, or the like—and is larger, preferably, at its inner end to receive the recess 7, while its outer end is somewhat reduced and preferably made with a many-sided contour—say octagonal. Spacing projections, as 10 10, 65 may be formed upon the outer end of the said block. Upon this end of the block is secured an attaching-cup 3, which is provided with a recess 11, made to conform to the contour of the insulating-block 1, it being preferably 70 flared upon its inner edge, as seen at 12. A suitable cement, as 13, is interposed between the attaching-cup and the insulating-block. Formed upon the attaching-cup, upon opposite sides thereof, are projections or flugs 14 14, 75 having bolt-holes 15 15 formed therein. These bolt-holes are preferably round in shape and are each provided with a rectangular countersunk portion, as at 16, which is adapted to receive the rectangular lower portion of the 80 heads 17 on the bolts 18. The shanks of the bolts 18 pass through the openings 15 and are secured in place by suitable nuts, as 19 19. The heads 17 are elongated and are bent inwardly at their outer ends, as at 20, so as to 85 overhang the flanges 21 21 of a conductor 4. Spacing projections, as 22, are preferably formed on the outer surface of the cup 3 to engage the insulator. The conductor 4 may be of any shape and material suitable for use in 90 conducting an electric current. The heads 17 of the bolts 18 18 are preferably formed so as not to press upon the flanges 21 of the conductor, a sufficient leeway being given for the conductor to have some movement upon the 95 cup 3. When it is desired to remove the conductor from the insulator, it is only necessary to loosen one of the bolts 18 slightly, so that its head 17 can be disengaged from the countersunk portion 16 and turned to one side. 100

This allows the flange of the conductor to be liberated from the cup. It will be apparent from the above description that our improved insulator is well adapted for holding all sorts of conductors which are for use upon electric railways and that the conductor will be supported in such a manner as to be thoroughly and effectively insulated from the base and other supporting means.

Having now described our invention, what we claim as new, and desire to secure by Letters Patent, is—

1. An insulator comprising an insulating-block having a recess at one end adapted to engage a base, a base for supporting the said block, spacing projections on said base for separating the block a suitable distance therefrom, an attaching-cup adapted to fit upon the other end of the said insulating-block, spacing projections on said block for separating the cup a suitable distance therefrom, means for holding the parts together, and means for securing a conductor to the said cup, substantially as described.

2. An insulator for supporting conductors, comprising a base having a projecting portion, spacing projections formed thereon, a cup for supporting a conductor, spacing projections on said cup for engaging said conductor, and an insulating-block interposed between the base and cup, the said block being provided at one end with a recess adapted to fit over the base and being adapted at its other end to engage a recess formed in the said cup, spacing projections on said block for engaging the cup, and cement or other adhesive material interposed between the parts

for holding them together, substantially as described.

3. An insulator comprising a base, an insulating-block and an attaching-cup, laterally-projecting lugs on said cup having bolt-holes therein, bolts having many-sided heads engaging the bolt-holes in the said cup, said holes having rectangular countersunk portions for engaging the many-sided heads of the bolts to prevent their turning, the heads upon the said bolts being adapted to overhang portions of a conductor for holding the same upon the cup, substantially as described.

4. An insulator for conductors comprising a base, an attaching-cup, an insulating-block for securing them together, apertured lugs formed upon the said cup and inclined toward the conductor, bolts adapted to fit in recesses in the said lugs, said bolts having head portions formed with rectangular bases adapted to fit in shallow countersunk portions in the said lugs so that the bolts cannot turn when secured in place, overhanging end portions formed on the said heads for embracing the flanges of a conductor, the structure being such that, by loosening one of the bolts and slightly lifting the head thereof out of the countersunk portion, it may turn to one side so as to liberate the conductor, substantially as described.

In testimony whereof we hereunto affix our signatures in presence of two witnesses.

JAMES THOMAS.

WILLIAM R. THOMAS.
